UNITED STATES PATENT OFFICE

JAMES H. SKITT, OF PHILADELPHIA, PENNSYLVANIA, ASSIGNOR TO SMITH, DRUM & COMPANY, OF PHILADELPHIA, PENNSYLVANIA, A CORPORATION OF PENNSYLVANIA

SAFETY APPLIANCE FOR WASHING MACHINES

Application filed May 1, 1929. Serial No. 359,455.

My invention relates to washing or dyeing machines or the like consisting of a casing provided with a sliding door, a container rotatably supported within the casing and a motor for actuating the container. The object of my invention is to provide a simple and efficient locking device adapted to lock the door in closed position and to so interengage with the door when the door is wholly or partly open that it cannot be moved to locking position and to so connect this locking device with a switch controlling the motor circuit that the switch can only be turned to close the circuit when the door is closed and locked. By preference I actuate both the lock and the switch through the switch handle lever and by preference also I so connect the switch handle lever with a brake for arresting the motion of the motor that the motion of the switch handle lever to open the circuit and retract the lock will apply the brake and my invention consists of the combinations of mechanisms by which I effect the above stated purposes.

The nature of my invention will be best understood as described in connection with the drawings which illustrate a washing machine provided with my improvements and in which

Figure 1 is an end elevation of the washing machine with portions of the casing broken away to exhibit details of construction.

Figure 2 is in effect a fragmentary enlargement of parts shown in Figure 1.

Figure 3 is a side elevation of the switch box and parts immediately connected therewith.

Figure 4 is a vertical section taken through the switch box on the line 4—4 of Fig. 2.

Figure 5 is a view illustrating the details of the transmission mechanism connecting the switch handle lever with the lock and the brake drum.

Figures 6, 7, and 8, are views shown partly in section showing the operation of the lock in connection with the door of the casing.

In the washing machine shown in the drawings, which is, generally speaking, of a familiar type, A indicates the casing, B the container secured to a shaft B¹ which ex-

tends through the ends of the casing and has secured to it a gear wheel B² which is engaged by a gear B³, driven in turn by a pinion B⁴, which pinion is actuated by a gear B⁵, driven in turn by a pinion B⁶ secured on the shaft of the motor indicated at C. C¹, Figure 2, indicates the brake strap which is actuated by a lever C² which in turn is actuated by the connecting rod F⁶. D indicates the switch box or casing which, as shown in Fig. 4, is provided with four contact members indicated at D¹ and D². D³ indicates a rotary switch drum provided with contacts, indicated at D⁴ and D⁵, which are moved out from beneath contacts D¹ and D², Fig. 2, at the beginning of the movement of the handle, thus breaking the circuit, the further movement of the handle to the left resulting in unlocking the door. The drum D³ is secured on shaft E¹ to which is also secured the switch handle lever, indicated at E.

F is a connecting rod connected at one end to the switch handle lever E and at its other end to a lever F¹ secured on a shaft F² from which also extends the lever arms F³ and F⁴. F⁵ and F⁶ indicate connecting rods of which the rod F⁵ is secured to an arm G of a bell crank lever G, G², pivoted at G¹ and having attached to or formed with the arm G² a locking bolt indicated at G³.

H, see Figures 6, 7, and 8, is the sliding door of the casing, the upper end of which is indicated at H¹ and which moves in guideways at the side of the casing, indicated at A¹; A² indicating an opening through the casing which is uncovered by the door when in fully closed position, as shown in Figures 7 and 8, and is closed by the door when the door is opened as shown in Figure 6.

The operation of the device can be readily followed when the door is fully closed, as shown in Figures 7 and 8; the switch handle lever E can be moved towards the position shown in Figures 1 and 2. This movement of the switch handle lever moves the lock to the position shown in Figure 8, the bolt G³ passing in front of the upper end of the sliding door H and securely locking it in closed position; further movement of the switch handle lever releases the brake band, 100

closes the circuit and energizes the motor to start the machine.

Whenever it is desired to open the door the switch handle lever must be moved towards the position shown in Figure 3. This movement of the lever handle opens the circuit, applies the brake and finally withdraws the locking bolt to a position which permits the door to be opened. The door may then be opened, the bolt being in the position shown in Figure 6, and the door then passes beneath the bolt, effectually locking it and through it the switch handle lever and the brake band so that the motor can not be started until the door is again fully closed.

It is advisable in machines of this kind to provide for what is called inching of the container so as to bring the door of the container into registry with the door of the casing and this can be effected by alternately opening and closing the circuit, energizing the motor which can be done when the bolt is in the intermediate position shown in Figure 7, in which position or transmission to which position it still securely locks the door in closed position but permits the switch lever to open and close the motor circuit.

Having now described my invention, what I claim as new and desire to secure by Letters Patent, is:

1. In a washing machine consisting of a casing having a sliding door, a container rotatably secured in said casing and a motor for actuating said container, the combination therewith of a lock operative to directly interengage with and lock the door of the casing when it is in closed position, and so interengagable with the body of the door when the lock is in retracted position that it is held in retracted position when the door is wholly or partly open, means for opening and closing the lock and a switch for opening and closing the motor circuit connected to the means for actuating the lock so as to open the circuit before the lock is retracted and prevent the closing of the circuit while the sliding door is open.

2. A washing machine having the features of claim 1, having also a brake for stopping the motor and a connection to the means for actuating the lock and switch whereby the brake is applied after the circuit is opened and as the lock is retracted.

3. A machine having the features of claim 1, in which the switch handle lever is connected to actuate the door lock.

4. A machine having the features of claim 1, in which the lock consists of a bolt secured on a bell crank lever pivoted on the body of the casing.

JAMES H. SKITT.
